(57) **CLAIM**

The ornamental design for an interlocking small-volume cryovial set, as shown and described.

DESCRIPTION

FIG. 1 is a side view of an interlocking small-volume cryovial set showing our new design with the interlocking small-volume cryovial set shown in an interlocked position; FIG. 2 is an exploded perspective view of the interlocking small-volume cryovial set; FIG. 3 is a cross-sectional view of the interlocking small-volume cryovial set taken along line 3-3 in FIG. 4; FIG. 4 is a top plan view of the interlocking small-volume cryovial set; and, FIG. 5 is a bottom plan view of the interlocking small-volume cryovial set.

1 Claim, 5 Drawing Sheets
